UNITED STATES PATENT OFFICE.

ALBERT B. SHULTZ, OF BUFFALO, NEW YORK.

LIQUID-LEVEL GAUGE.

Application filed May 3, 1922. Serial No. 558,094.

To all whom it may concern:

Be it known that I, ALBERT B. SHULTZ, a citizen of the United States, residing in Buffalo, in the county of Erie and State of New York, have invented new and useful Improvements in Liquid-Level Gauges, of which the following is a specification.

This invention relates to a gauge which is designed to indicate the variations of the level of a liquid and more particularly to a gauge of this character which may be used on the radiator of an automobile for the purpose of indicating the height of the water therein and thus enable the attendant 10 to replenish the radiator with water from time to time, as required, for maintaining the same in the highest state of efficiency 15 and also avoid injury to the parts associated with the radiator.

It is the object of this invention to provide a liquid gauge for this purpose which is comparatively simple and inexpensive in construction, which can be readily applied to the standard types of radiators now on 20 the market and which will give a reliable indication when the water in the radiator is below normal.

In the accompanying drawings: Figure 1 is a vertical sectional elevation of an automobile radiator equipped with my improved liquid gauge. Figures 2 and 3 are horizontal sections taken on the correspondingly numbered lines in Fig. 1.

Similar characters of reference refer to 35 like parts throughout the several views.

My invention is useful for indicating the variations in the level of a liquid which may be contained in receptacles of various kinds, but more particularly the water level within 40 the upper tank or box 10 of an automobile radiator, which latter is provided in its top with an upright filling nipple or collar 11 through which the water is introduced from time to time to replenish waste due to leak- 45 age and evaporation. Ordinarily this fill- ing collar 11 is closed by means of an ordinary screw cap, which is detachably connected with the collar by means of a screw joint and provided in its top 13 with a cen- 50 tral opening 14.

My improved liquid gauge is mounted on this cap or cover and in its preferred form the same is constructed as follows:

Projecting downwardly through the open- 55 ing 14 in the top of the filler cap is a tubular nipple or body 15 which in its preferred

form has its lower end provided with an internal flange 17, the central part of which is provided with a perforation 18. Above the filler cap is arranged a hood, dome or casing 19 of hollow form which in the preferred construction is of larger diameter than the nipple and has its lower end connected with the upper end of the same by a horizontal web 20 which forms a downwardly facing shoulder 16 on the underside of the web engaging the upper side of the top 13, said nipple, dome and web being preferably formed in one piece by casting or otherwise. On the upper part of the front and rear 70 sides of this hood the same is provided with sight openings 21, 21, which permit of observing the interior of this hood from the front and rear sides thereof.

Sliding vertically in the opening 18 and 75 guided by the latter is an upright shifting rod 22, the upper part of which terminates within the hood and is provided in the latter with an indicator head 23 which in the preferred form has the shape of a sphere, as shown in Figs. 1 and 2, and is connected with the shifting rod by means of a screw joint. To the lower end of this shifting rod is secured a float 24 which is adapted to ride 80 on the liquid within the tank or receptacle 10 and rise and fall therewith in response to variations in the level of the liquid within the tank. This float may be of any suitable construction, but as shown in the drawings, the same is preferably made in the 85 form of a hollow sheet metal body and secured by means of a screw joint to the lower end of the shifting rod.

The nipple 15 is secured in place on the 90 filler cap by means of a clamping screw nut 25 engaging with an external screw thread on the lower end of this nipple and bearing against the underside of the cap top 13 through the medium of an interposed washer 26, thereby holding the nipple 15 and hood 19 in place on the filler cap and also forming a leak-tight joint between the same. On one side, the clamping nut 25 is provided with a downwardly projecting guide arm 27 which latter is provided at its lower end 100 with a guide eye 28 which receives the lower part of the shifting rod 22 above the float and serves in connection with the guide opening 18 to guide this shifting rod in its vertical movements and maintain the float 105 and indicator head in their proper positions.

When the level of the liquid in the tank or

receptacle 10 is at the proper height, the float 24 riding on the water will raise the shifting rod and the indicator head 23 into such a position that this head will be visible 5 to the attendant through the sight openings 21 in the hood. If, however, the liquid level in the tank drops below normal the corresponding drop of the float which descends with the level of the liquid will carry the indicator head 23 downwardly so that the same will be either wholly or partly concealed from view through the sight opening and thus warn the attendant that the water supply in the tank requires replenishing. It 10 will therefore be evident that by these means the attendant can always keep a careful watch on the supply of water in the radiator without necessitating the removal of the filler cap for this purpose and thus ensure 15 maintaining the radiator in its highest state of efficiency and preventing injury to any of the parts associated therewith, which would be liable to occur if the water level becomes unduly low or exhausted.

20 By mounting this liquid gauge on the radiator filler cap the same is removed from the radiator tank with the cap and restored thereto as a unit, thereby avoiding the use of any extra parts which are liable to become misplaced and also avoiding the necessity of altering the tank or operative parts of the radiator for the purpose of applying 25 this liquid gauge thereto.

In its general organization this liquid 30 gauge is very simple in construction and reliable in operation and is sightly in appearance.

I claim as my invention:

1. A liquid level gauge comprising a cap 35 adapted to be mounted on the receptacle containing the liquid to be gaged and having an

opening in its top, a nipple arranged in said opening and having a shoulder at its upper end and an internal perforated flange at its lower end, a hood arranged at the upper end 40 of said nipple and having a sight opening, a vertically movable shifting rod guided in the perforation of said flange and provided at its upper end with an indicator head which is adapted to move vertically relative 45 to said sight opening, a float mounted on the lower end of said rod and adapted to respond to variations in the height of the liquid in said receptacle, a screw nut arranged on the lower part of said nipple and 50 engaging with the underside of the top of said cap, and a guide arm depending from said screw nut and provided at its lower end with an eye in which the lower part of said shifting rod is guided.

2. A liquid level gauge comprising a cap 55 adapted to be mounted on the receptacle containing the liquid to be gaged and having an opening in its top, a nipple arranged in said opening and having a laterally extending web forming a downwardly facing shoulder which engages with the top of said cap and an internal perforated flange at its lower end, a hood of larger diameter than 60 said nipple and having its lower end connected with said web and provided in its upper part with a sight opening, a vertically movable shifting rod sliding in the perforation of said lower flange and provided at 65 its upper end with an indicator head which is movable vertically relatively to said sight opening, means for securing said nipple in said cap, and a float arranged at the lower end of said rod and adapted to rise and fall 70 with the liquid level in said receptacle.

ALBERT B. SHULTZ.
